MOORING BITT

Karl C. Kortum, Petaluma, Calif.

Application May 2, 1946, Serial No. 666,748

8 Claims. (Cl. 114—218)

1

This invention relates to new and useful improvements and structural refinements in mooring bitts, more specifically, to a combination mooring bitt and chock, such as may be effectively employed for the fastening of hawsers, cables, or the like, which are commonly employed for mooring ships to the dock.

The invention applies particularly to the mooring bitts positioned on the ship's deck and the principal object of the invention is to provide a device of the character herein described, such as may be employed with substantially improved results, in place of the conventional rope stopper. In existing practice, this stopper, which is of a considerably smaller diameter than the hawser, is secured at one end to the mooring bitt, while its remaining end is wound several times around the hawser to be secured. The rope stopper is thus momentarily subjected to withstand the entire strain on the hawser, this practice not only being a dangerous and a tedious operation, but also frequently resulting in considerable damage to both the stopper and the hawser itself.

It is therefore a further object of the invention to eliminate the disadvantages above outlined by providing a mooring bitt in which a wedge co-acts with an eccentric sheave to firmly and securely stopper the hawser within the mooring bitt structure.

Another object of the invention is to provide a mooring bit in which friction is reduced to a minimum and in which the actual stopping strain is absorbed by the sheave and the wedge, rather than by the hawser or cable.

An additional object of the invention is to provide a mooring bitt structure which is adapted for mounting adjacent to the rail on the deck of a vessel and which, being so positioned, will eliminate the use of the conventional chock.

A further object of the invention is to provide a mooring bitt which does not need to be accurately aligned with the nigger head or capstan, in order to facilitate satisfactory operation thereof.

Another object of the invention is to provide a mooring bitt in which the conventionally experienced slackening of the hawser subsequent to the securing thereof, is eliminated.

A further object of the invention is to provide a mooring bitt which will generally increase the utility, speed and effectiveness usually associated with the operation of bitts of conventional design.

A still further object of the invention is to provide a mooring bitt which is simple and compact.

2 in construction and which will not easily become damaged.

With the above more important objects in view, and such other objects as may become apparent as this specification proceeds, the invention consists essentially of the arrangement and construction of parts as illustrated in the accompanying drawings, in which:

Figure 1 is a plan view of the invention, illustrating the same in situ on the ship's deck.

Figure 2 is a side elevation of the same, partially broken away to reveal its construction, and

Figure 3 is a cross-sectional view, taken in the plane of the line 3—3 in Figure 1.

Like characters of reference are used to designate like parts in the specification and throughout the several views.

Referring now to the accompanying drawings in detail, the invention consists of a flat, horizontal base 5, formed integrally with a pair of spaced, upstanding bitts 6, the same being of conventional design and configurated substantially as shown in the accompanying drawings.

25 The base 5 is provided between the bitts 6 with a bore 7 and a counter bore 8, and a substantially vertical spigot, consisting of the shank 9 and the head 10, is positioned in the bores 7 and 8, as is best shown in Figure 3.

30 An eccentric sheave 11 is rotatably mounted on the shank 9, this sheave being retained in position thereon by means of a retainer 12. The latter is placed in a suitable seat 13 provided in the sheave 11, the retainer being internally threaded and adapted to engage a screw-threaded portion 14 formed at the upper end of the shank 9. A plurality of tommy-bar apertures 15 are formed in the retainer, whereby the same may be firmly and securely tightened.

35 The sheave 11 is inscribed with the arrow 16 for designating its eccentricity and a plurality of radially disposed sockets 17 are also formed in the sheave, the same being hereinafter more particularly described.

40 The mooring bitt as a whole is mounted in any suitable manner on the deck 18 of the vessel, adjacent to the side rail 19. The latter is formed with the usual hawser opening 20 and the hawser 21 enters through this opening and passes around the sheave 11, as will be clearly apparent from the accompanying drawings.

45 The sheave 11 is formed with a concaved peripheric groove 22 and the hawser passes completely around the sheave, forming a spiral coil. The remaining end 23 of the hawser 21 is taken

3

to a suitable nigger head or capstan (not shown). The bitts 6 are recessed adjacent the lower ends thereof to provide flat surface portions 24 and a wedge 25 is removably receivable in either of these recesses, as will now be described.

One side, that is, the hawser contacting side 26 of the wedge 25 is tapered in both horizontal and vertical planes with respect to its relatively opposite side 27, the side 26 extending upwardly and outwardly, as is best illustrated in the accompanying Figure 2.

When the invention is placed in use, the outer end of the hawser 21 is connected in any suitable manner to the dock and the hawser is passed through the opening 20 and around the sheave 11, 15 as has been already set forth.

The end 23 of the hawser is connected to the nigger head or capstan and it will be apparent that by hauling in the hawser, the sheave 11 will be rotated in the direction of the arrow 28. When the hawser has been tightened to the desired amount, the wedge 25 is inserted between the sheave and the surface 27 of the bitt 6, as will be clearly apparent from the accompanying drawings.

The hawser may now be slackened a little, or alternatively, a tommy-bar 29 may be inserted into one of the sockets 17 and the sheave 11 rotated in the anti-clockwise direction, so that the eccentricity of the sheave co-acts with the wedge 25 and the side 26 crimps or bears against one section of the hawser, designated by the reference character 30.

The hawser will now be held firmly and securely and it should be pointed out that inasmuch as the wedge 25 contacts the hawser at only one particular section (30), the securing strain will be evenly distributed through the portion of the hawser coiled around the sheave. It should be particularly noted that the lower section 31 of the hawser does not contact the wedge 25, as is best illustrated in the accompanying Figure 2.

The bitt may be simply and speedily released by "backing off" the sheave in the direction of the arrow 28 through the medium of the tommy-bar 29 or alternatively, by tapping the end 32 in order to dislodge the wedge from its stopping position.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A mooring bitt structure comprising in combination, a base and an upstanding bitt thereon, an eccentric sheave rotatably mounted on said base adjacent to said bitt, said bitt being provided with a flat surface portion adjacent to said sheave, a hawser passing around said sheave, and a wedge, said wedge co-acting with said flat surface portion and with said sheave to stopper said hawser.

4

2. A combined mooring bitt and chock structure comprising in combination, a base and a pair of spaced, upstanding bitts thereon, an eccentric sheave rotatably mounted on said base between said bitts, said bitts being formed with flat surface portions adjacent to said sheave, a hawser passing around said sheave, and a wedge, said wedge co-acting with one of said flat surface portions and with said sheave to stopper said hawser.

3. The device as defined in claim 2 which is adapted for mounting adjacent the rail on the deck of a vessel.

4. A combined mooring bitt and chock structure comprising in combination, a flat, horizontal base and a pair of spaced, upstanding bitts thereon, a substantially vertical spigot also on said base between said bitts, an eccentric sheave rotatably positioned on said spigot, said bitts being recessed to form flat surface portions adjacent to said sheave, a hawser passing around said sheave, and a wedge, said wedge co-acting with one of said flat surface portions and with said sheave to stopper said hawser.

5. The device as defined in claim 4, in which said sheave is formed with a plurality of radially disposed sockets, said sockets being adapted to receive a tommy-bar.

6. The device as defined in claim 4, in which said hawser passes around said sheave in a plurality of spiral coils, the hawser contacting surface of said wedge being adapted to engage only one of said coils.

7. A combined mooring bitt and chock structure comprising in combination, a flat, horizontal base and a pair of spaced, upstanding bitts formed integrally with said base, a substantially vertical spigot on said base between said bitts, an eccentric sheave rotatably positioned on said spigot and formed with a concave peripheric groove, said bitts being recessed to provide flat surface portions adjacent to said sheave, a hawser passing around said sheave in a plurality of spiral coils, and a wedge, one side of said wedge being tapered in horizontal and vertical planes with respect to the relatively opposite side thereof, said tapered side being engageable with one of said coils of said hawser, and said wedge co-acting with one of said flat surface portions and with said sheave to stopper said hawser.

8. The device as defined in claim 7, in which said sheave is inscribed with an arrow for designating the eccentricity thereof.

KARL C. KORTUM.
